UNITED STATES PATENT OFFICE

2,466,481

AUTOMOBILE DOOR LOCKING DEVICE

John M. Royal, Bristol, Conn.

Application November 8, 1945, Serial No. 627,301

1 Claim. (Cl. 292—144)

1

This invention relates to improvements in locking devices for automobile doors.

The primary object of the present invention is to provide means whereby all of the doors of a motor vehicle may be locked simultaneously by a single operation.

A further object of the invention is to provide a device of the above kind whereby the locks on all of the doors of a motor vehicle may be simultaneously conditioned for unlocking by a single operation and then unlocked individually by actuation of the bolt-releasing handle on the outside of each door.

Still another object of the invention is to provide a device of the above kind which is simple and may be readily installed upon existing automobile door locks, and which is highly efficient in operation and convenient to use.

The exact nature of the present invention will become apparent from the following description when considered in connection with the accompanying drawings, in which the figure is a view partly in section and partly diagrammatic, showing a preferred embodiment of the invention.

Referring in detail to the drawing, the locks for the doors of an automobile of the sedan type are respectively indicated at A, B, C, and D. The locks are all alike and only the lock A is shown complete. As is usual, each lock includes a casing 5 having a sliding bolt 6 therein that may be retracted from within the automobile by means of an interior handle, not shown. The bolt 6 is normally projected by a spring 7 and may also be manually retracted from outside the automobile by manipulation of the usual exterior handle, not shown. The shaft 8 of the exterior handle is journaled transversely of the casing 5 and has a cam 9 fixed thereon within the casing, said cam bearing against an abutment 10 of the bolt 6 so that when the shaft 8 is turned in an anti-clockwise direction as viewed in the figure, bolt 6 is retracted. The exterior handle, shaft 8 and cam 9 may also be returned to normal position, when the exterior handle is released, by means of a spring 11.

In accordance with the present invention, a detent 11 is mounted in the casing 5 and projected by a spring 12 to normally prevent sufficient rocking movement of the cam 9 to effect release of the bolt 6 from its keeper. The detent 11 is preferably slidably mounted as shown for rectilinear movement and disposed so that an end of the same engages within a notch 13 of the cam 9. It will be noted that there is a slight space between the end of detent 11 and

2

the adjacent wall of the notch 13 so that limited rocking movement of the cam 9 is permitted, when the exterior handle is turned to partially retract the bolt 6. The other end of detent 11 carries an armature 14, and mounted within the casing 5 in position to attract the armature 14 are electromagnets 15. When the armature 14 is attracted by the electromagnets 15, the detent 11 is retracted so as to release the cam 9 and permit sufficient rocking movement of the latter to release the bolt 6. The present locking means also includes a suitable key-controlled switch 16 and an auxiliary switch 17, the latter being mounted in the casing 5. As shown, the switch 17 includes an adjustable contact 18 insulated from the casing 5 and arranged to coact with a pivoted contact 19 whose free end is engaged with the cam 9 and which is yieldingly urged toward the contact 18 by spring 20. The contact 18 is shown as a screw adjustably threaded through an insulating block 21 fixedly mounted in the casing 5, said casing having an aperture 22 through which a screw driver may be inserted to facilitate adjustment of the contact 18. The spring 20 is weaker than the spring 7, and the arrangement is such that when the bolt 6 is projected, cam 9 is positioned to engage contact 19 and swing it out of engagement with contact 18. On the other hand, when cam 9 is rocked for the limited extent allowed by detent 11, contact 19 is moved by spring 20 into engagement with contact 18. Switch 16 may be termed a master switch and may be suitably mounted so as to be accessible outside the automobile body. Switch 17 may be considered an auxiliary switch, the switches 16 and 17 being in series with each other and the electro-magnets 15. As shown, a battery 23 having one side grounded at 24, is connected at its other side to one terminal of switch 16 by a wire 25 having a fuse 26 interposed therein. The other terminal of switch 16 is connected to one terminal of one of the electro-magnets 15, and one terminal of the other electro-magnet is connected by a wire 28 with the contact 18 of lock A, the electro-magnets 15 of the latter lock being connected in series, and the contact 19 of said lock A being grounded as at 29. The electromagnets 15 and switches 17 of the other locks B, C, and D are similarly connected in series, but with those of each lock in parallel with those of the other locks.

In use, the switch 16 is locked in open position so that the electromagnets 15 are deenergized and the detents 11 are projected by their springs

12 to prevent sufficient rocking movement of the cams 9 of the locks to effect retraction and release of the bolts 6 of the locks. The bolts of the locks are thus held projected so that the doors of the automobile are maintained in locked condition. To unlock the doors, switch 16 is closed, and the exterior handle of each lock is operated to turn the associated cam 9 and permit closing of the associated switch 17. As soon as such associated switch 17 is closed, the circuit of the associated electromagnets 15 will be closed and such magnets will release the associated detent 11 so that turning of the exterior handle may be continued and the associated bolt 6 retracted sufficiently to unlock the door. The only door which will be unlocked is that whose exterior handle is turned, so that each individual door must be separately unlocked by manipulation of its exterior handle. When the bolts of the locks are projected again the associated switches 17 will be opened so as to de-energize the electromagnets and permit projection of the detents 11 for locking the bolts in projected position. The switch 16 is then locked in open position so that manipulation of the exterior handles of the locks may not effect release thereof unless the master switch 16 is unlocked and closed by an authorized person possessing the key to the switch 16.

From the foregoing description, it is believed that the construction, operation and advantages of the present invention will be readily understood and appreciated by those skilled in the art. Minor changes and modifications may be made, such as fall within the scope of the invention as claimed.

What I claim is:

An automobile door lock including a casing having a horizontally sliding bolt therein, a rocking cam manually operable from outside the door

to release said bolt, a spring projected horizontally reciprocable detent co-acting directly with said cam at one end for normally preventing sufficient rocking movement of the cam to effect release of the bolt but permitting limited rocking movement thereof, said detent being parallel with and beneath the bolt, an armature fixed on the other end of said detent, electromagnetic means for attracting said armature to retract the detent and permit sufficient rocking movement of the cam to release the bolt, and a switch in the casing below the pivot of the cam, said switch being in series with said electro-magnetic means for controlling energization of the latter, said switch being directly controlled by said cam to open the circuit of said electro magnetic means when the bolt is fully projected and to close said circuit when said cam is manually actuated to give it the limited rocking movement normally permitted the same by said detent, said switch further including a fixed contact and a movable contact spring-biased into engagement with the fixed contact when the bolt is retracted and held out of engagement with said fixed contact by the lower end of said cam when the bolt is projected.
